[57] ABSTRACT

In a hydraulic system, a proportional flow valve is used for automatically paying-out line as a crane boom is extended so that extension of the boom will not draw up the hook or cause damage if there is no free line. The proportional flow valve diverts to the winch motor some of the hydraulic fluid directed by a manual valve toward the boom-extending cylinder. The necessary pressure in the line to the winch motor, required for actuating a safety valve in the return line from the winch motor, is achieved through the use of a special reversing valve for the winch motor. This reversing valve has a combination closed and open center spool so that when centered it blocks the line to which fluid is diverted while leaving open the return line.

SYSTEM FOR AUTOMATICALLY PAYING-OUT LINE PROPORTIONAL TO EXTENSION OF CRANE BOOM

INTRODUCTION

Hydraulically extendable booms for cranes have become very common and popular. Throughout their use, they have presented an attendant problem that when the boom is extended has the same effect as drawing in the line. A load hanging by the line is drawn closer to the tip of the boom, and if there is not enough free line something must give, and damage can result. When the hook or the block by which it is carried is tight against the pulley or block at the tip of the boom, the line between the pulley and the winch binds the boom against extension. Although damage could be prevented by setting the relief valve for the boom-extending hydraulic fluid at a sufficiently low value, this is undesirable because a higher value is sometimes needed. A long-practiced partial solution to the problem is to place the boom extension and winch control valve handles adjacent one another so that they could be operated with one hand. For inexperienced operators this is an unreliable and awkward remedy. Even experienced operators can make mistakes. In some cranes, using one hand for these two valves may be objectionable.

Schemes known heretofore for automatically paying-out the line as the boom was extended have not proved popular and perhaps have not really been practicable.

According to the present invention, the line is automatically payed out as the boom is extended, with complete dependability and at low equipment cost, by utilizing a proportional flow regulator connected to divert to the winch motor some of the hydraulic fluid which would otherwise be used entirely for extending the boom. This valve represents substantially the only additional equipment cost required by this invention. Although the winch control valve needs a special spool, this is merely furnished in place of that which would otherwise be used. Some very inexpensive check valves may also be required, unless their function is inherent in the proportional flow regulator.

Additional advantages and objects of the invention may be apparent from the following description and from the drawings.

DESIGNATION OF FIGURES

FIG. 1 is a simplified side view of a mobile crane having an extensible or telescopic boom with which the present invention may be used.

FIG. 2 is a diagrammatic circuit diagram representing the present invention.

DESCRIPTION OF SPECIFIC EMBODIMENT

The following disclosure is offered for public dissemination in return for the grant of a patent. Although it is detailed to ensure adequacy and aid understanding, this is not intended to prejudice that purpose of a patent which is to cover each new inventive concept therein no matter how others may later disguise it by variations in form or additions or further improvements. The claims at the end hereof are intended as the chief aid toward this purpose, as it is these that meet the requirement of pointing out the parts, improve-

ments, or combinations in which the inventive concepts are found.

FIG. 1 illustrates a hydraulic truck crane mounted on a vehicle 10. The crane comprises a base 11 which usually can swing about a vertical axis. This carries a proximal boom section 12, sometimes called a "shipper" for pivotal movement about a horizontal pin 13. A distal boom section 14 is telescopically received in proximal boom section 12. A hydraulic cylinder 15 is connected between base 11 and boom section 12 to pivot the boom about pin 13. A hydraulic motor 16, commonly called a crowd cylinder, is connected between boom sections 12 and 14 to control the extent to which they are telescoped with respect to each other. A hoist line 17 extends from a winch 18 about a pulley 19 on the end of the boom. Winch 18 is operated by a hydraulic motor 20. There may be more than one distal or telescoping boom section, each operated by a crowd cylinder.

Referring to FIG. 2, the hydraulic cylinder defining motor 16 is double acting and has hydraulic connections 23 and 24. When fluid under pressure is supplied to connection 23, the boom is extended, i.e., boom section 14 moves out from its nested position within boom section 12. When hydraulic fluid is supplied to connection 24, the boom is retracted, i.e., section 14 moves further within section 12. A conventional reversing valve or manual control valve 25 has three positions. It is resiliently urged toward the center of these three positions by means such as springs 26. A conduit 27 connects valve 25 with a source of fluid pressure as represented by pump 28. A conduit 29 connects valve 25 with discharge, as represented by sump 30.

A conduit 32 connects valve 25 with connection 24. A conduit 33 connects valve 25 with a check valve 34 and with the input of a proportional flow regulator 35. One output 36 of the proportional control regulator is connected by a conduit 37 to a check valve 38. A conduit 39 connects check valves 34 and 38 with cylinder connection 23.

The second output 43 of the proportional flow regulator is connected by a conduit 44 to a check valve 45. The constrictive orifices indicated on the proportional flow regulator 35 are to indicate diagrammatically that the hydraulic fluid delivered to the input of the flow regulator through conduit 33 are proportionally divided between the respective outputs 36 and 43. In other words, a proportion of the flow valve 25 directs toward the crowding function and diverted to the line pay-out function. The screw 46 associated with one of these orifices is to indicate that the relative proportion of the flow through each of the outputs of the regulator may be varied. One valve suitably used for proportional flow regulator 35 is that available from Fluid Controls as their No. 2F24-P-6-6-6-40S.

Another reversing or manual control valve 49 has three positions and is resiliently urged to the center of the three positions, as suggested by springs 50. A conduit 51 connects valve 49 to a suitable source of hydraulic fluid, as indicated by pump 52. A conduit 53 connects the valve to discharge, as indicated by sump 54. All sumps indicated are actually a common tank from which the pump can draw. Pressure line 51 has a pressure relief valve 55 communicating therewith. A similar pressure relief valve 55 communicates with pressure line 27 from pump 28.

A conduit 58 connects valve 49 with check valve 45 and with connection 59 of motor 20. A conduit 60 connects valve 49 with a pilot-actuated valve apparatus 61. The valve apparatus 61 is connected by a conduit 62 to a connection 63 on motor 20.

The valve apparatus 61 comprises a check valve 65 in parallel with an automatically actuated valve 66. Valve 66 is controlled by a hydraulic cylinder 67 responsive to the pilot pressure in conduit 58, as indicated by the fine line 58'.

With the two valves 25 and 49 in their central position, as illustrated in FIG. 2, both of the motors 16 and 20 are stationary. The fluid from pump 28 is recirculating through the sump 30. The fluid from pump 52 likewise is recirculating to sump 54. This fluid is applying some pressure in a direction tending to open check valve 65, but the pressure is relatively low because of being open to the sump 54. Furthermore, the conduit 58 at the opposite side of motor 20 is blocked at valve 49 and at check valve 45. Thus, motor 20 is not operating.

If the line 17 is to be wound on winch 18 (raising the load), valve 49 is shifted to open connections represented by assuming that the right end of the valve diagram is aligned with the conduits. This applies fluid pressure to conduit 60 and connects conduit 58 to the sump 54. Thus, fluid pressure will flow through check valve 65, motor 20 and return through conduit 58. If the load is to be lowered, the valve 49 is shifted oppositely to open connections represented by the left hand end of the valve diagram so that fluid pressure is supplied to conduit 58 and conduit 60 is connected to the sump. As conduit 58 is pressurized it actuates hydraulic cylinder 67 to open valve 66 so that the hydraulic fluid from motor 20 can flow through conduit 62, through valve 66 to conduit 60 and then to the sump.

If the boom 12, 14 is to be retracted, the valve 25 is moved to the left so that fluid under pressure is applied to conduit 32 and conduit 33 is connected to sump 30. Thus, the hydraulic fluid flows to connection 24 of cylinder 16. The hydraulic fluid from the cylinder flows from connection 23 through check valve 34 to return to the sump through conduit 33. A safety or pilot actuated valve similar to valve 61 would ordinarily be present adjacent connection 33 but is omitted for simplification.

If the boom is to be extended, the valve 25 is moved to the right so that conduit 33 is connected to the pump 28 and conduit 32 is connected to sump 30. Fluid from conduit 33 flows through the proportional flow regulator 35 to output 36 and through check valve 38 to connection 23 of the motor 16. The fluid from the motor, of course, discharges through conduit 32 to the sump 30. However, a proportion of the fluid from conduit 33 also flows to the second output 43 of the proportional flow regulator 35. This fluid proceeds through check valve 45 to conduit 58. As it pressurizes conduit 58 it opens valve 66 as previously described so that the fluid from motor 20 can flow through 62, 60 and 53 to the sump 54. The pressurized fluid in conduit 58 being derived from the proportional flow regulator also flows through motor 20 to actuate motor 20 in the direction such as to pay out the hoisting line 17.

As initially explained, if the hoisting line 17 was not payed out, there would be a danger that something

would be broken by the extension of boom 12, 14. This can be visualized with reference to FIG. 1 where it will be seen that if boom section 14 moves to the right the portion of line 17 below pulley 19 will decrease drawing the block 70 toward the pulley 19. Conceivably, these can be brought into contact by the extension of the boom, thereby resisting any further extension of the boom, so that if further extension were attempted, damage would result. However, through the use of the present invention, the line 17 is payed out as the boom is extended so that the extent of the line 17 outboard of pulley 19 is not significantly decreased and the danger of damage is eliminated. Theoretically, the adjustment of proportional flow regulator 35 would be such that during extension of the boom block 70 would stay at a constant distance from pulley 19. Actually, such precision is not likely to be obtained or constant, and the regulator 35 should therefore be adjusted to cause a slight increase of the spacing of block 70 can be made by operating valve 49.

Because of the proportional flow nature of valve 35 it accommodates itself to varying rates of flow provided by valve 25 from "cracking open" to full open. Throughout the range, it maintains at least roughly the movement of 17 at least equal to the crowding movement of boom section 14.

I claim:

1. A hydraulic system for a crane having a boom which is telescopic under control of a crowd cylinder having extend and retract conduits and a reversing "crowd" valve to be extended when the valve passes pressured fluid to its "extend" conduit leading to one cylinder port and makes a connection for the other cylinder port to discharge;

the crane also having a hoist line extending in part longitudinally along the boom and paying out to lower a load under control of a winch motor and a three-position reversing "line" valve having up and down conduits when the "line" valve passes pressured fluid to the "down" conduit leading to the winch motor and makes a connection for the other winch motor conduit to discharge, said other conduit having a pilot-actuated safety valve preventing flow through said other conduit from the winch motor to discharge except when pressured fluid is supplied to the "down" conduit, characterized by:

a proportional flow regulator connected to receive fluid from the "crowd" valve when in the "crowd" setting and to proportion the flow thereof between the "crowd" motor for extending the boom and the "line" motor means for paying out the line; said three-position reversing "line" valve when in its middle position blocking flow from the "down" conduit to discharge while providing a passage for flow from the other winch motor conduit to discharge.

2. A hydraulic system for a crane having a boom which is telescopic under control of a crowd cylinder having extend and retract conduits and a reversing crowd valve to be extended when the valve passes pressured fluid from a crowd pump to its "extend" conduit leading to one cylinder port and makes a connection for the other cylinder port to discharge; the crane also having a hoist line extending in part longitudinally

along the boom and paying out to lower a load under control of a winch motor and a three-position reversing "line" valve having up and down conduits when the "line" valve passes pressured fluid from a line pump, having its output separate from the output of the crowd pump, to the "down" conduit leading to the winch motor and makes a connection for the other winch motor conduit to discharge, said other conduit having a pilot-actuated safety valve preventing flow through said other conduit from the winch motor to discharge except when pressured fluid is supplied to the "down" conduit, characterized by:

an adjustable proportional flow regulator connected to receive fluid from the crowd valve when in the crowd setting and to proportion the flow thereof between the crowd motor for extending the boom and the "line" motor means for paying out the line; whereby the line is payed out when the boom is extended, but at a relative rate which is adjustable;

said three-position reversing "line" valve when in its middle position blocking flow from the "down" conduit to discharge while providing a passage for flow from the other winch motor conduit to discharge.

3. A hydraulic system for a crane having a boom which is telescopic under control of a crowd cylinder having extend and retract conduits and a reversing crowd valve to be extended when the valve passes pressured fluid from a crowd pump to its "extend" conduit

10 leading to one cylinder port and makes a connection for the other cylinder port to discharge; the crane also having a hoist line extending in part longitudinally along the boom and paying out to lower a load under control of a winch motor and a three-position reversing "line" valve having up and down conduits when the "line" valve passes pressured fluid from a line pump, having its output separate from the output of the crowd pump, to the "down" conduit leading to the winch

15 motor and makes a connection for the other winch motor conduit to discharge, said other conduit having a pilot-actuated safety valve preventing flow through said other conduit from the winch motor to discharge except when pressured fluid is supplied to the "down" conduit, characterized by:

an adjustable proportional flow regulator connected to receive fluid from the crowd valve when in the crowd setting and to proportion the flow thereof between the crowd motor for extending the boom and the "line" motor means for paying out the line; whereby the line is payed out when the boom is extended, but at a relative rate which is adjustable;

20 said three-position reversing "line" valve when in its middle position blocking flow from the "down" conduit to discharge; but said valves providing a passage for flow from the other winch motor conduit to discharge when the crowd valve is set for extending the boom.
